L. H. OHLEN

RADIATOR HANDLING DEVICE

Filed Feb. 2, 1922

INVENTOR.
LOUIS H. OHLEN.
BY HIS ATTORNEY.
James F. Williamson

UNITED STATES PATENT OFFICE.

LOUIS H. OHLEN, OF DELL RAPIDS, SOUTH DAKOTA.

RADIATOR-HANDLING DEVICE.

Application filed February 2, 1922. Serial No. 533,589.

To all whom it may concern:

Be it known that I, LOUIS H. OHLEN, a citizen of the United States, residing at Dell Rapids, in the county of Minnehaha and State of South Dakota, have invented certain new and useful Improvements in Radiator-Handling Devices; and I do hereby declare the following to be a full, clear, and exact description of the invention, such as will enable others skilled in the art to which it appertains to make and use the same.

This invention relates to a supporting device for the radiator of an automobile. As is well known to those skilled in the art, such radiators often need repair and in handling the same for such repair it is necessary to turn the same over and hold them in various positions.

It is an object of this invention to provide a device arranged to support and hold the radiator therein in clamped position, which device is mounted for movement about a plurality of axes at right angles to each other whereby the radiator can be conveniently moved to various positions for the operations thereon.

It is more particularly an object of this invention to provide a supporting means for the radiator whereby the position of the same can be changed conveniently by one workman, said means comprising in the embodiment of the invention illustrated, a circular wedge disk and clamping means engaging the same.

These and other objects of the invention will be fully set forth in the following description made in connection with the accompanying drawings, in which like reference characters refer to the same parts throughout the different views, and in which,

Fig. 1 is a top plan view of the device; and

Fig. 2 is a view in side elevation thereof, as seen from the lower side of Fig. 1.

Referring to the drawings, a support 1 is shown which may be one side of a suitable table or work bench or any other support to which it may be desired to attach the device. A plate 2, shown as of circular form, is bolted to the support 1, and a plate 3 is cen-

trally pivoted to the plate 2 and adapted to rotate thereon about said pivot. Preferably an anti-friction bearing will be supplied between the plates 2 and 3. The plate 3 has secured thereto or integral therewith a pair of spaced circular wedge members or disks 4 being formed somewhat less than a complete circle in extent. As clearly shown in Fig. 2, these disks are quite narrow adjacent the plate 3 but increase in width away from said plate. These disks are provided with circularly formed slots 4^a concentric with a central pivot bolt 6^a to which is pivoted a bar 6 having its end disposed between the disks 4 and provided with an opening therethrough adapted to receive a clamping screw 7 provided with a handled shoulder at one end, which screw also passes through the slots 4^a and is provided at its other end with a clamping nut 8. The bar 6 has bolted to its other end a pair of disk members 5 formed similarly to the disks 4 and provided with similar slots 5^a. A bar 9 is centrally pivoted to the disks 5 by a headed and nutted bolt extending centrally therethrough and this bar is also provided with an aperture for receiving a clamping screw 10 similar to the clamping screw 7, which clamping screw also is provided with the clamping nut 11. The bar 9 extends outwardly from the disks 5 and has disposed thereon a member 12 preferably rectangular in cross section, which is held thereon by a collar at the outer end of the bar 9 secured by a suitable set screw. Members 13 have inwardly facing angle members 14 bolted to their adjacent sides, are mounted for sliding movement on the bar 10, and arranged to be clamped in various positions on said bars by handled clamping screws 15. The members 13 also have projecting from their upper ends threaded bolts 16 and a bar 18 having slots adjacent each end through which the bolts 16 pass, is provided and adapted to be clamped down on the radiator *a* shown in dotted lines, and to be held in such clamped position by the winged nuts 17.

In the use of the device, the radiator *a* will be positioned on the angle members 14 which will be moved into close engagement

2
with the sides thereof and held in such position by tightening the members 13 on bar 12 by the screws 15. The sliding movement of members 13 relative to the bar 18 is permitted by the slots in the end of the latter. The bar 18 will now be clamped on the top of the radiator, as shown in Fig. 2, by clamping nuts 17. The radiator thus supported can be swung about a vertical axis 10 extending centrally of the plates 2 and 3 and can be moved to different positions by swinging the bar 9 about the center of the disks 5 and swinging bar 6 about the center of the disks 4. By providing the wedge disks 4 and 5, the device can be easily operated by one workman. If it is desired to swing the bar 9 about its pivot, the workman can somewhat support the bar 12 and the radiator with one arm and slightly loosen the screw 10. The radiator will then drop a short distance until the clamping shoulder of the screw 10 and the nut 11 bind on the wedge surfaces of the disks. The screw can then again be slightly turned and the radiator again thus slightly lowered. By allowing the supported radiator to thus move through small increments, the desired position can be obtained and the screw 10 tightly clamped. The same operation can be performed in moving the bar 6. The bar 12 can, of course, be swung upwardly at all times and held in slightly raised upward position by turning the handles of the screws 7 or 10.
35 From the above description it is seen that applicant has provided a simple and very efficient radiator handling device and one which will have great utility for its intended purpose. The parts are few in number and can be made quite rugged, so that there will be no tendency for the parts to become disarranged when once assembled.

It will, of course, be understood that various changes may be made in the form, details and arrangement of the parts without departing from the scope of applicant's invention, which, generally stated, consists in the matter shown and described and set forth in the appended claims.

50 What is claimed is:

1. A radiator handling device having in combination, means for clamping and holding a radiator, a member extending from said means, means for swingingly supporting said member including a circular wedge, and adjustable means for clamping said circular wedge whereby said member may be successively swung to different positions.

60 2. A radiator handling device having in combination, a member adapted to be secured to a support, a member rotatable on said member about a vertical axis and comprising a circular wedge disk disposed substantially in a vertical plane, means pivoted to the disks to swing about a horizontal axis,

and comprising a device for holding a radiator, and means engaging the wedge surface of said disk to hold said last mentioned means in various positions.

3. A radiator handling device having in combination, a member adapted to be secured to a support, a member rotatable on said member about a vertical axis and comprising a circular wedge disk disposed substantially in a vertical plane, means pivoted to the disk to swing about a horizontal axis, and comprising a second circular wedge disk, a member pivoted thereto to swing about a horizontal axis and carrying a radiator clamping and supporting device, and means engaging the circular wedge disks and the means and members pivoted thereto to hold the same in various positions.

4. A radiator handling device having in combination means adapted to be attached to a support, a member pivoted thereto to swing about a vertical axis comprising a pair of spaced oppositely facing circular wedge disks disposed in substantially vertical planes, a bar pivoted to said disks to swing about a horizontal axis and carrying at its outer end a similar pair of disks, means engaging the first mentioned disks for holding said bar in various positions, a bar pivoted at one end between said second pair of disks to swing about a horizontal axis and having a radiator supporting and clamping device at its other end, and means engaging said second mentioned disk and clamping said last mentioned bar thereto in various positions.

5. A radiator handling device having in combination, a bar, members slidable thereon toward and from each other to engage and support a radiator, a bar carried by said members and extending therebetween adapted to clamp the top of the radiator, and means for supporting said first mentioned bar for movement about vertical and horizontal axes.

6. The structure set forth in claim 5, said last mentioned means comprising a link to one end of which said first mentioned bar is pivoted by a horizontal pivot, said link being supported at its other end for swing movement about vertical and horizontal axes.

7. A radiator handling device having in combination a device for supporting and clamping a radiator, a member extending from one end thereof, and means for supporting said member for swinging movement about vertical and horizontal axes including a pair of spaced circular wedge disks disposed in substantially vertical planes, said disks having circular slots therethrough, and clamping means extending through said slots and engaging said disks and member to clamp the latter in various adjusted positions.

8. A device for handling a radiator or similar article having in combination, means for clamping and holding the radiator, means for swinging said radiator about axes at right angles to each other including a swivelled joint comprising a disk having one of its surfaces at an angle to the other to

form a wedge, and a member movable toward and from said surface to control the movement of said disk whereby the parts of the joint may be moved by successive increments.

In testimony whereof I affix my signature.

LOUIS H. OHLEN.
